CLAIM

The ornamental design for a headset for headmounted display, as shown and described.

DESCRIPTION

FIG. 1 illustrates a top, front, and left side perspective view of a headset for headmounted display showing our new design;

FIG. 2 illustrates a top, rear, and left side perspective view thereof;

FIG. 3 illustrates a top plan view thereof;

FIG. 4 illustrates a right side elevational view thereof;

FIG. 5 illustrates a left side elevational view thereof;

FIG. 6 illustrates a bottom plan view thereof;

FIG. 7 illustrates a front elevational view thereof; and,

FIG. 8 illustrates a rear elevational view thereof.
